UNITED STATES PATENT OFFICE

CHRISTIAN FLEISSNER, JR., OF NEWARK, NEW JERSEY

DESIGN FOR EMBOSSED LEATHER OR SIMILAR ARTICLE

Application filed April 7, 1930. Serial No. 35,181. Term of patent 14 years.

To all whom it may concern:

Be it known that I, CHRISTIAN FLEISSNER, Jr., a citizen of the United States, residing at Newark, in the county of Essex and State of New Jersey, have invented a new, original, and ornamental Design for Embossed Leather or Similar Article, of which the following is a specification, reference being had to the accompanying drawings, forming part thereof.

In said drawings, the figure illustrates a face or plan view of embossed leather or similar article showing my new design, one repeat unit of which is enclosed within the dot and dash lines appearing thereon.

I claim:—

The ornamental design for embossed leather or similar article, as shown and described.

Dated this 3rd day of April, 1930.

CHRISTIAN FLEISSNER, JR.
